Abraham Sawyer 1771X
Letter Patent

The Schedule referred to in these Letters Patent and making part of the same containing a description in the words of the said Abraham Sawyer himself of his improved Grist Mill.

The improvement consists principally in the alteration of the spindle used in the common Grist Mill, by lengthening, or continuing the same through the ~~horn~~¹ of the mill to a ~~frame~~ just above the uppermost stone or ~~runner~~². To this frame the spindle is fastened, instead of being fastened in the bed stone as formerly.² The frame is fastened by means of four posts set fast in the building, two on opposite sides of the mill stones. Into the posts on the back, (at the ~~horn~~¹ of a Grist Mill as now used) is a straight piece of iron with a mortice through the centre of the frame for the admission of the spindle. This iron or iron cast on a shoulder in the spindle, supports or turns the runner or grinding stone.² The part of a grist mill most liable to injury & which could not be repaired without taking up the mill, was the fastening of the spindle which turns the runner. The old mode was to confine it by means of a box and wedges in the bed or ~~bottom~~³ stone below where the top of the spindle entered the horn which turns the runner. This was frequently out of repair, the wedges were soon worn out, or the box burned up, by the friction of the spindle. This is entirely remedied by fastening the spindle above the ~~horn~~¹ side of the hopper (a little higher than the top of the runner) in such a roller or timber with coarse tenons, into this roller insert two & sticked a timber of sufficient strength to keep the spindle steady. These timbers are to be connected by ~~expanses~~⁴ at such a distance that they will just fall between the other two posts. Let one of the wgs bars⁵ come immediately over the eye of the mill stone. This bar is to support the top of the spindle. The spindle will be connected with this wgs bar several ways. The top can be round, and con-

in a mortise in the bar, or a screw of sufficient length with a square point can be fixed perpendicular through the bar, which point will stand in a socket at bottom in the top of the spindle, or the spindle can be made. (3) The object of the collar is to permit the frame to be turned back, when the mill is taken up. (4) The object of two sticks is to support the hopper. In mills that will permit two posts one on opposite sides of the stone with a beam across will answer the purpose. (5) This bar will be better in two pieces and fastened together with screws or keys and should be made of hard wood or iron. (6) This socket will be better made in a piece of abundance steel, & set into the top of the spindle in two pieces, the upper part affixed to the lower just above the horn, (sufficiently strong) with a socket in the top to meet the point of the screw. A wrought iron affixed to the end of the frame which lies between the posts of sufficient pressure to keep the same in its place, and still permit the frame to rise as the runner is raised and fall as it is lowered. (7) A further improvement can be had by fastening the horn to the top of the runner instead of the bottom. This is done in the following manner. Drill mortises for the horn into the top of the stone (say five or six inches) then mortises for two bars of iron to lie across the ends of the horn with holes up each end of the iron bars. these bars are to be fastened in their places with bolts and keys, as follows. Drill four holes through the stone for them. This I think the better way, for by taking the top part of the spindle off, the runner can be taken up, without raising, it so high as in the other ways. If the latter mode is used the top part of the spindle should be made eight square or flat to fit the grain from the stone. In the other mode a piece of wood should encircle the spindle for that purpose. A mill keyed in this way, will run steady, and easily and will be secure from the jar and danger arising from the looseness of the spindle, and from the heat occasioned by friction in the old manner. (8) These holes are to be larger at the bottom than the

1971X

be top road to admit the heads of the bolts as far into the stone as
it will ever be used. Then with keys through the top of these bolts
be iron band are fastened down. In hanging a corner in this
manner, there must be washers or rings of iron to elevate the
spindle to keep the horn a proper distance from the shoulder
(the spindle which washers can be taken off at the stone wall
corner.
